DESIGN FOR A HEAD TRUCK FOR CLEANERS

Roy B. Everson, Chicago, Ill.

Application June 12, 1937, Serial No. 69,805

Term of patent 14 years

To all whom it may concern:

Be it known that I, Roy B. Everson, a citizen of the United States of America, residing at Chicago, in the county of Cook and State of Illinois, have invented a new, original, and ornamental Design for a Head Truck for Cleaners, of which the following is a specification, reference being had to the accompanying drawing, forming a part thereof.

In the drawing:

What I claim is:

The ornamental design for a head truck for cleaners, as shown.

ROY B. EVERSON.
